ABSTRACT OF THE DISCLOSURE

A process for preparing high V.I. lube oils of high quality in improved yield comprising fractionating the stock material into three fractions, boiling at (a) from 720–855° F., (b) 855 to 980° F. and (c) the residuum or a fraction boiling at from 986–1070° F., solvent extracting fraction (b) with a solvent having preferential solubility for aromatics such as furfural, recombining the three fractions, and hydrocracking the combined fractions at from 720 to 800° F. using a hydrogen partial pressure of from 2,000 to 3,000 p.s.i. The higher boiling fraction is deasphalted if required.

BACKGROUND OF THE INVENTION

In the past various processes have been used for upgrading lubricating oils and other petroleum fractions. Recent developments in hydrocracking techniques has created increased interest in commercial utilization of this technique of obtaining lube oils of increased viscosity index.

SUMMARY OF THE INVENTION

The present invention relates to a hydrocracking process wherein the feed stock is prepared so as to provide an improved yield of a product lube oil having a high viscosity index. In general this preparation involves vacuum fractionating an atmospheric residuum into three lube stock streams which are:

(a) A distillate boiling in the range of 720 to 855° F. (true boiling point hereinafter TBP).
(b) A distillate boiling from 855° F. TBP to a point in the range of from 980° F. to 1070° F. TBP depending on the particular crude and product lubes, requirements and.

(c) A fraction boiling above fraction (b) which may be a distillate boiling at from 980–1070° F. TBP or a residuum boiling at above 1070° F. (TBP). The fraction (b) is solvent extracted with a solvent having preferential solubility for aromatics to produce a dewaxed oil having a viscosity index 10 to 30 viscosity index units above the dewaxed oil viscosity index of the charge. (As used herein viscosity index or V.I. is determined by ASTM D-2270). The depth of this extraction generally is greater for lower V.I. charge stocks such as those having a V.I. of 30 to 60 than for charge higher V.I. charge stocks such as those having a V.I. of from 60 to 90. In general suitable solvents for this extraction include furfural, acetophenone, phenol, mixtures of phenol and cumene, acetonitrile, nitrobenzene, aniline, 2,2-dichlorodiethyl ether, dimethyl sulfoxide and mixtures thereof. The particular solvent selected is dependent on several considerations such as economics, the depth of extraction required, and characteristics of the particular crude from which the fraction is derived. Generally furfural and phenol are the preferred solvents. The temperature at which the extraction is performed must be below the temperature of miscibility of the oil and the

2

solvent in order to have any extractive separation, and usually is well below the temperature of miscibility for an efficient operation with good yields of raffinate. Since the present invention normally does not involve dewaxing the charge stock the lower temperature limit for solvent extraction is that temperature at which solids appear in the stock being solvent extracted. The temperature range encompassing all of the suitable operating temperatures for all of the suitable solvents is about 0° to 350° F. In the case of furfural, however, a temperature in the range of about 125 to 325° F. is preferably employed. The ratio of solvent to oil to be used is somewhat interdependent on the particular temperature being used. Generally, solvent to oil ratios in the range of 6:1 to 0.25:1 are suitable with ratios of from 4:1 to 0.8:1 being the preferred range. The equipment employed in carrying out the solvent extraction is not critical and any conventional solvent extraction equipment can be used such as rotating disc contactors, Podbielniak reactors and countercurrent packed bed extraction columns. Either a batch or continuous operation may be used.

When the third component is a vacuum residuum boiling above 1070° F., it should be deasphalted such as by conventional propane deasphalting to produce a deasphalted oil with a Ramsbottom carbon content of no greater than 2.0 wt. percent. In accordance with the present invention no further upgrading of this component is required. If the third component is a distillate, such as that boiling in the range of from 960 to 1070° F. no upgrading is required. These components are blended to form a hydrocracker charge containing from 20 to 70 volume percent of component (a), from 30 to 50 volume percent of the raffinate of component (b) and from 10 to 40 volume percent of component (c).

The blend feed stock is hydrocracked at from 2,000 to 3,000 p.s.i. hydrogen partial pressure. The hydrocracker is generally operated at a LHSV (liquid hourly space velocity) of from 0.5 to 1.5. The hydrocracker is best operated at a temperature of from 720 to 800° F. Generally any sulfactive hydrogenation catalyst can be used in the hydrocracking step. These catalysts are sulfides of the Group VI-B and Group VIII metals and preferably combinations thereof, for example nickel sulfide, and either tungsten sulfide, or molybdenum sulfide. Preferably the catalyst is supported on a carrier such as alumina or silica-alumina. The preferred catalyst is sulfided and fluorided nickel-tungsten supported on silica-alumina.

The hydrocracker generally produces a waxy lube stock boiling above 650° F. which is 60 to 90 vol. percent of the hydrocracker charge and preferably greater than 70 vol. percent of the hydrocracker charge. This depends on the precise feed blend prepared and the viscosity index level desired. As the desired viscosity index of the lubes increases less of component (c) above can be tolerated in the feed blend and more of component (a) is required.

DESCRIPTION OF THE PREFERRED EMBODIMENTS

In the examples, Example I is illustrative of the present invention and Examples 2 to 5 illustrate the results obtained using other refining techniques. In each of Examples 1 to 5 the crude used in a Lagomedia crude having a gravity, API° of 33, a sulfur content of 1.2 wt. percent, a viscosity of 54 Saybold universal seconds at 100° F., a pour point of 0° F. and an O.D. color of 21,000. In each of the extractions in the examples is carried out using furfural in a volume solvent to oil ratio of 1.5 to 1.0 at 220° F. The properties of the various components as used in Examples 1, 3, 4, and 5 are reported in Table I.

TABLE I

Component A, unex- tracted	Component B		Component C	
	Unex- tracted	Extracted	Unex- tracted	Extracted
API gravity at 60° F.....	25.7	26.1	27.6	19.2
Initial boiling point, ° F.....	686	815	652	589
50% point, ° F.....	777	923	923	998

Viscosity at 210° F., Cst.....	5.2	15.6	11.4	26
1 842° F./98%; 2 992° F./98%; 3 993° F./98%; 4 1,030° F./78%.				18.8

The properties of the components used in Example II are reported in Table II. (Both components are unextracted)

TABLE II

	Compo- nent A	Compo- nent B
API gravity at 60° F.....	26.2	23.2
Initial boiling point, ° F.....	670	717
50% boiling point, ° F.....	791	908
End point/recovery.....	(1)	(2)
Viscosity at 210° F., Cst.....	5.32	11.97

1 877° F. 98%; 2 947° F. 98%.

In each of Examples I and V the catalyst used is sulfided nickel-tungsten supported on silica-alumina, containing minor amounts of fluoride and available under the trade-name GC-6 from Gulf Oil Corporation. The properties of the various hydrocracked lubes and the amounts of the various feed components used in Examples I to V are reported in Table III.

As can be seen from Table III the present invention as illustrated in Example I results in a substantially improved yield while maintaining a high viscosity index in the various lube fractions.

We claim:

1. A process for the preparation of lube oils comprising fractionating a crude into a fraction (a) boiling principally at from about 720° F. to 855° F., a fraction (b) boiling principally at from about 855° F. to from 980 to 1070° F. and a fraction (c) boiling above fraction (b) solvent extracting fraction (b) with a solvent having a preferential solubility for aromatic compounds, combining this raffinate with the other two fractions which fractions contain their original aromatic compounds exclusive

of asphaltic compounds to form a hydrocracker feedstock and catalytically hydrocracking said hydrocracker feed stock at from about 720 to 800° F., a hydrogen partial pressure of from 2,000 to 3,000 pounds per square inch.

2. The process of claim 1 wherein fraction (c) boils at from about 980° F. to 1070° F.

3. The process of claim 2 wherein the solvent extraction is carried out using a ratio of solvent to oil from 4 to 1 to 0.8 to 1.

4. The process of claim 3 wherein the solvent is furfural.

5. The process of claim 4 wherein the solvent extraction is carried out at from 125° F. to 325° F.

25 6. The process of claim 5 wherein fraction (a) constitutes from 20 to 70 volume percent of the hydrocracker charge stock, the raffinate of fraction (b) constitutes from 30 to 50 volume percent of the hydrocracker feed stock, and fraction (c) constitutes from 10 to 40 volume percent of the hydrocracker feed stock.

7. The process of claim 6 wherein the hydrocracking catalyst is sulfided nickel-tungsten.

50 8. The process of claim 7 wherein the catalyst is supported on silica-alumina.
